[57] CLAIM

The ornamental design for a sailboat hull, as shown and described.

DESCRIPTION

FIG. 1 is a right side elevational view of a sailboat hull showing my new design, the broken lines are for illustrative purposes only and form no part of the claimed design;

FIG. 2 is a top plan view thereof;

FIG. 3 is a left side elevational view thereof;

FIG. 4 is a bottom plan view thereof;

FIG. 5 is a rear elevational view thereof;

FIG. 6 is a front elevational view thereof;

FIG. 7 is an enlarged fragmentary perspective view of the aft portion of the cockpit thereof;

FIG. 8 is a cross sectional view thereof taken along lines 8—8 of FIG. 3;

FIGS 9 through 19 are peripheral outline views thereof taken along lines 9—9 through 19—19 of FIG. 3.
